UNITED STATES PATENT OFFICE.

WILLIAM G. WEBER, OF RIDGEFIELD PARK, NEW JERSEY, ASSIGNOR TO KOPS BROS.,
OF NEW YORK, N. Y., A FIRM.

CLASP.

1,421,874.

Specification of Letters Patent.

Patented July 4, 1922.

Application filed September 15, 1921. Serial No. 500,884.

To all whom it may concern:

Be it known that I, WILLIAM G. WEBER, a citizen of the United States, residing at Ridgefield Park, in the county of Bergen 5 and State of New Jersey, have invented an Improvement in Clasps, of which the following is a specification.

My present invention relates to clasps and more particularly to that type of clasp employed in corset garments to connect the 10 front steels thereof to one another when the garment is in position on the body of the wearer, although as will be understood the invention is not limited to this particular use. Heretofore, in clasps of the type to which my invention relates, particularly when applied to corset garments the same have been so constructed as to permit a relative movement of one of the corset steels 15 to the other tending to throw the outer or forward edge of one of the corset steels toward the body of the wearer to such an extent in some cases as to make the garment uncomfortable. This, as will be readily apparent, is due to the fact that the stud member of the clasp has a shank sufficiently long to permit of considerable lateral play or movement in the hook or socket member 20 when the parts are connected. This results in the relative movement between the corset steels when the garment is on the body in which the steel to which the stud members of the clasps are attached is shifted to the 25 position in which its outer edge or the edge adjacent the steel to which the socket members are attached is moved inwardly while of course the opposite edge of the steel is moved outwardly. This causes the planes of the steel to assume an angular position 30 and the edge of the steel to which the studs are attached to extend inwardly or toward the body to such an extent as hereinbefore as in many cases to be uncomfortable and in all instances to be undesirable. The object 35 of my invention is to overcome this difficulty and in doing so I provide the usual form of stud and socket or hook member connected to the corset steels in the usual manner and I provide the socket members with oppositely placed lugs or projections which may be made therein in any suitable manner so that when the parts of the clasps are connected the stud members at one side thereof are engaged in the bases 40 of the recesses and the heads at the oppo-

site sides thereof are in contact with these bosses or projections which obviously maintains the corset steels in substantially the same plane irrespective of the tension which may be applied to the clasps in securing the 60 garment in position on the body.

In the drawing:

Fig. 1 is an elevation illustrating the front portion of a corset fitted with my improved clasps. 65

Fig. 2 is an enlarged cross section on line 2-2, Fig. 1, and

Fig. 3 is an enlarged cross section on line 3-3, Fig. 1.

Referring particularly to the drawing, I 70 have illustrated my improved clasp as applied to a corset garment. In this form of the invention one of the corset steels is indicated at 10 and the other at 11. The corset steel 11 is provided with a plurality of 75 spaced studs 12 each comprising a shank 13 having a flange 14 and an up set end 15 by which it is connected to the corset steel, while at the other or outer end the stud is provided with a head indicated at 16. 80 The other corset steel 10 is provided with a corresponding number of hook or socket members 17. These are connected to the steel in the same spaced positions as the studs are secured in the steel 11 and as indicated this connection is made by rivets 18. 85 As is customary each of the socket members is slotted at 19 in such a manner as to receive the corresponding stud member. Preferably the upper portion of the slot or that 90 adjacent the steel is sufficiently large to receive the head of the stud which is caused to pass through the same, while the outer or base of the slot as indicated at 20 is adapted to receive the shank of the stud. 95 As illustrated each of these socket members is provided with oppositely disposed projections indicated at 21 and 22 placed in the material in positions at or adjacent the edge defining the slot therein and approximately 100 midway between the inner and outer ends of the slot or in positions as to engage with the under side or surface of the head of the stud when the shank thereof is in position in the base of the slot.

The fabric body of the garment is connected to the steels in the usual manner. On one side this fabric body is indicated at 23 and is connected to the steel 11, while on the opposite side or in the other corset 110

body half the fabric body of the garment 24 is suitably connected to the steel 10.

As will now be understood when the parts are in position and as is clearly indicated in Figs. 2 and 3 of the drawing, the shank 5 of each stud engages the base of a slot in the corresponding socket member, while the projections 21 and 22 engage the under surface of a head of the corresponding stud so that because of this engagement and the fact that the outer end of the socket or hook member is caused to lie against the material covering the steel in which the stud is mounted prevents the stud steel from shifting 10 relatively to the socket steel causing the steels to assume and to be maintained in substantially the same plane and thus preventing the outer edge of the stud steel from projecting inwardly and exerting undue 15 pressure along the line thereof on the body of the wearer.

I claim as my invention:

1. A clasp comprising a stud having a head, and a socket member having a slot 25 therein with ribs on both sides of the slot intermediate of the ends thereof and having

a continuously rounded surface sloping into the body of the socket member.

2. A clasp comprising a stud member having a head, and a socket member having a slot 30 therein with depressions in the inner surface of the socket member forming ribs on the outer surface thereof on both sides of the slot intermediate of the ends thereof, the surface of each rib being continuously 35 rounded and sloping to the edges of the slot and also into the body of the socket member.

3. A clasp comprising a stud member having a head, and a socket member having a slot 40 therein with depressions on the upper surface of the socket member providing ribs on the outer surface thereof on both sides of the slot intermediate of its ends, each rib having a substantially quartispherical surface whereby when the stud is in position 45 in the socket member a portion of the head of the stud extends beyond the top edge of each rib.

Signed by me this 13th day of September, 1921.

WILLIAM G. WEBER.
